CLAIM

The ornamental design for a dongle, as shown and described.

DESCRIPTION

FIG. 1 is a front perspective view of a dongle constructed in accordance with the invention;

FIG. 2 is a bottom rear perspective view of the dongle as shown in FIG. 1;

FIG. 3 is a front view of the dongle as shown in FIG. 1; FIG. 4 is a right side view of the dongle as shown in FIG. 1;

FIG. 5 is a rear view of the dongle as shown in FIG. 1; FIG. 6 is a left side view of the dongle as shown in FIG. 1;

FIG. 7 is a top elevational view of the dongle as shown in FIG. 1; and,

FIG. 8 is a bottom elevational view of the dongle as shown in FIG. 1.

The broken lines shown in the drawings depict portions of the dongle that form no part of the claimed design.
